UNITED STATES PATENT OFFICE.

GAETANO ALBANESE, OF RICHMOND HILL, NEW YORK.

DESIGN FOR A BARBER SIGN.

Application filed January 15, 1929. Serial No. 29,619. Term of patent 14 years.

To all whom it may concern:

Be it known that I, GAETANO ALBANESE, a citizen of the United States, and residing at Richmond Hill, L. I., in the county of Queens and State of New York, have invented a new, original, and ornamental Design for Barber Signs, of which the following is a specification, reference being had to the accompanying drawing, forming part thereof.

The figure is a front elevation of a barber sign, showing my new design.

I claim:

The ornamental design for a barber sign, as shown.

GAETANO ALBANESE.
